CLAIM

We claim the ornamental design for a wristband strap set, as shown and described.

DESCRIPTION

FIG. 1 is a rear view of a first wristband strap of a wristband strap set.

FIG. 2 is a right side view of the first wristband strap of FIG. 1.

FIG. 3 is a front view of the first wristband strap of FIG. 1.

FIG. 4 is a left side view of the first wristband strap of FIG. 1.

FIG. 5 is a bottom view of the first wristband strap of FIG. 1.

FIG. 6 is a top view of the first wristband strap of FIG. 1.

FIG. 7 is a rear view of a second wristband strap of the wristband strap set.

FIG. 8 is a left side view of the second wristband strap of FIG. 7.

FIG. 9 is a front view of the second wristband strap of FIG. 7.

FIG. 10 is a right side view of the second wristband strap of FIG. 7.

FIG. 11 is a top view of the second wristband strap of FIG. 7.

FIG. 12 is a bottom view of the second wristband strap of FIG. 7.

FIG. 13 is an isometric view of the first wristband strap of FIG. 1.

FIG. 14 is an isometric view of the second wristband strap of FIG. 7.

FIG. 15 is an isometric view of the wristband strap set with the first and second straps of FIGS. 1 and 7 shown in a configuration of use; and,

FIG. 16 is an isometric view of the wristband strap set with the first and second straps of FIGS. 1 and 7 in an alternate configuration of use.

FIGS. 1 through 16 are drawn to-scale within each Figure, although the scale from Figure to Figure may vary.

Stipple shading is used in the accompanying Figures to convey surface contouring, not texture. Features depicted using broken lines and a lack of shading indicate environmental structure that forms no part of the claimed design. The rectangular dashed boundary around the text indicates a boundary between the claimed design and text that forms no part of the claimed design.
